MEANS AFFORDING A DETACHABLE CONNECTION BETWEEN A BLADE UNIT AND A PRESSURE UNIT THEREFOR

John W. Anderson, Gary, Ind.

Application June 6, 1956, Serial No. 589,723

1 Claim. (Cl. 15—245)

This invention relates generally to windshield wipers and more particularly to a wiper which will wipe a curved or flat windshield.

The wiper may be constructed in various ways, but as herein shown comprises a blade assembly and a pressure-distributing device operatively connected to the blade assembly. The blade assembly includes a resilient wiping element and a resiliently flexible support detachably connected to the element. The pressure device preferably includes a pair of secondary yokes having their ends connected to the blade assembly at longitudinally spaced points, a primary yoke or bridge having its ends connected to intermediate portions of the secondary yokes, and a connector carried by the primary yoke for attachment with a wiper arm.

With the foregoing in mind, the principal object of the invention is to provide improved connection means whereby to facilitate assembly of the blade assembly and pressure device during manufacture and replacement of a new blade assembly when required.

The detachable connection is preferably comprised of cooperating components formed on the blade assembly and pressure device as distinguished from separate fittings or fasteners for obtaining the connection. More specifically in this regard, the connection includes providing the support of the blade assembly with a pair of longitudinally spaced abutments for receiving therebetween an end of one of the secondary yokes. One of the abutments is preferably made rigid and the other yieldable or flexible so that when the blade assembly is slid lengthwise into connection with the pressure device an end of one of the secondary yokes will cause retraction of the yieldable abutment until the end engages the rigid abutment, whereupon the yieldable abutment will automatically return or snap back to its original position and lock the said end of the yoke between the abutments. The arrangement is preferably such that separation of the blade assembly and pressure device can be readily effected after merely actuating or depressing the yieldable abutment to an extent permitting release of the locked end of the secondary yoke from between the abutments.

Significant features of the invention reside in locating the rigid abutment adjacent one end of the support so that only the opposite end of the support can be introduced for slidable connection with either extremity of the pressure device, and in locating the yieldable abutment so that the first extremity of the pressure device which is slid onto the said opposite end of the support will eventually cause retraction of the yieldable abutment when the secondary yokes of the device are properly mounted on the support.

Another object of the invention is to provide the rigid abutment by offsetting transversely a portion of the support and the yieldable abutment by forming a yieldable tongue extending lengthwise of the support, and preferably locating the abutments upwardly so they cannot accidentally scratch a windshield as the blade assembly is moved thereon.

2

A further object of the invention is to provide a blade assembly which offers a reduction with respect to costs in manufacture and assembly as compared to an arrangement in which separate fittings or fasteners are employed to obtain a connection between a blade assembly and a pressure device.

Additional objects and advantages of the invention will become apparent after the description hereinafter set forth is considered in conjunction with the drawings 10 annexed hereto.

In the drawings:

Figure 1 is a side elevational view of a wiper comprising a blade assembly and a pressure device therefor, showing a fixed and a yieldable abutment on the support of the blade assembly for locking purposes;

Figure 2 is an enlarged partial top view of the wiper illustrated in Figure 1;

Figure 3 is an enlarged partial side elevational view of the wiper depicted in Figure 1; and

Figure 4 is a partial elevational end view of the blade assembly illustrated in Figure 1, with portions in section to illustrate certain structural details.

As exemplified in Figures 1 through 4 of the drawing, the blade assembly or unit includes a resiliently flexible support generally designated 1 and a resilient wiping element 2. The support and wiping element may be attached in various ways, but as illustrated the support is elongate, of substantially uniform thickness and provided with a longitudinal narrow slot 3 terminating short of the ends of the support to provide connecting portions. Thus, longitudinal parallel portions 4 of the support can be spread apart to enlarge the slot so that the wiping element 2 can be properly located therein, after which the longitudinal portions are released for interlocking connection with the wiping element.

The wiping element is preferably formed in one piece and provided with opposed longitudinally extending exterior grooves 5 therein to provide a neck 6. These grooves receive the inner marginal edges of the longitudinal portions 4 with the neck between such portions so that portions of the element engage the upper and lower surfaces of the support as depicted in Figure 4. The element is preferably further formed with a second pair of opposed longitudinally extending grooves 7 to provide a hinge 8 to obtain a controlled pivotal movement of a wiping head 9 having wiping edges thereon as shown.

The pressure unit or device may be designed and constructed in various ways, but as disclosed herein is preferably comprised of a plurality of relatively movable members, such as a pair of secondary yokes 10 and 11 having their ends mounted on the support at longitudinally spaced points, a primary yoke 12 having its ends pivoted to intermediate portions of the secondary yokes, and a connector 13 carried by the primary yoke for attachment with a fitting on a wiper arm, not shown.

The secondary yokes are preferably identical in design and construction. Each end of each secondary yoke includes a transverse portion 14 which overlies that portion of the wiper element above the support and a pair 60 of opposed laterally offset portions or ears 15 which are substantially U-shaped in cross section for slidably embracing the exterior longitudinal marginal edges of the support as clearly depicted in Figure 4.

The connection utilized to detachably connect the blade assembly and pressure device may be designed and constructed in various ways, but as exemplified herein includes a pair of spaced abutments carried by one of the units. More specifically in this regard, the connection preferably includes providing one of the longitudinal portions 4 of the support with an upturned relatively rigid transverse abutment 16 and the other longitudinal portion with a yieldable abutment 17 preferably in the form of

an upturned flexible longitudinally extending finger or member, inclined at an acute angle with reference to the plane of the support so that its free end faces or points generally toward the rigid abutment. The abutments are preferably formed by striking or deforming portions of the support and if found desirable may be otherwise formed and located in positions different from those shown. Attention is directed to the fact that the flexible abutment 17 is located between the longitudinal marginal edges of one of the longitudinal portions of the support; that the abutment 16 is preferably formed transverse to the grain of the material from which the support is made and is, therefore, relatively rigid as against thrust in a direction longitudinally of the blade assembly; and that the abutments preferably project upwardly and not laterally from the sides of the support so they cannot scratch the windshield when the blade assembly is moved thereon. The abutments are preferably located adjacent one extremity of the support and longitudinally spaced a predetermined distance apart so as to provide means for receiving or accommodating the outer eared end or part of either of the secondary yokes, depending on which of these yokes is first slid into connection with the support.

The mode of connecting and disconnecting the blade assembly and pressure device is easily and quickly accomplished by merely moving the device toward the right as viewed in Figure 1 so that the left end of the support will successively receive the ears 15 on the secondary yokes 11 and 10 and when the device is moved farther to the right the outer end of the yoke 11 will engage and retract the finger 17 and when said end leaves the finger and/or engages the fixed abutment 16 the yieldable finger will automatically return to a normal locking position and thereby lock the end between the abutments. The abutment 16 not only serves as a stop to locate an outer end of one of the secondary yokes with respect to the yieldable abutment during connection of the units, but normally prevents an individual from sliding the pressure unit over the right end of the blade assembly. In other words, the organization described primarily affords a locking of the units by introducing only one end of the

blade assembly into either end of the pressure device. However, if the occasion requires, the relatively rigid abutment can be depressed to effect a separation of the units, in which event the yieldable abutment will be retracted when the secondary yokes are moved back over the abutment 16.

Having thus described my invention, it is obvious that various modifications may be made in the same without departing from the spirit of the invention; and, therefore, 10 I do not wish to be understood as limiting myself to the exact form, construction, arrangement and combination of parts herein shown and described.

I claim:

15 In combination: a windshield wiper blade unit and a pressure unit, said blade unit comprising an elongate resilient wiper element and an elongate resiliently flexible support therefor said support comprising side portions disposed in substantially the same plane and having inner edges engaging opposite sides of the element and outer substantially parallel edges, and one of said side portions being provided with a fixed abutment and the other side portion with a resiliently flexible abutment spaced longitudinally from the fixed abutment, said abutments being located adjacent one extremity of the support and between its outer edges, said pressure unit including a pressure-distributing part mounted on the side portions between the abutments for holding the units together, said 20 resiliently flexible abutment being operable to automatically lock the part between the abutments when the units are brought into proper engagement and also being manually operable to permit separation of the units.
